(57) **CLAIM**

We claim the ornamental design for a boot, as shown and described.

DESCRIPTION

FIG. 1 is a right side view of a boot showing the design.

FIG. 2 is a top view of a boot shown in FIG. 1.

FIG. 3 is a left side view of a boot shown in FIG. 1.

FIG. 4 is a bottom view of a boot shown in FIG. 1.

FIG. 5 is a front view of a boot shown in FIG. 1; and, FIG. 6 is a rear view of a boot shown in FIG. 1.

The broken lines represent portions of the boot that form no part of the claimed design.

The broken lines which define the bounds of the claimed design form no part thereof.

1 Claim, 3 Drawing Sheets

FIG. 1**FIG. 2**

FIG. 3**FIG. 4**

FIG. 5**FIG. 6**
